COMBINATION LIGHTER AND BURNER
SUPPORT FOR GAS STOVESStanley H. Hobson, Rockford, Ill., assignor to
Geo. D. Roper Corporation, Rockford, Ill., a
corporation of Illinois

Application July 16, 1930, Serial No. 468,283

45 Claims. (Cl. 126—39)

This invention relates to gas stoves and has more particular reference to a combination lighter and burner support for the cooking top.

Automatic lighters have been applied to gas stoves for several years operating on the flashback principle of Methudy patent No. 1,675,899, according to which principle, when the gas for a burner is turned on, some gas is conducted through a tube to a pilot light where it is ignited and the flame flashed back through the tube to the burner. It has been common practice to provide the automatic lighter for the cooking top in the form of a spider with the pilot light casing at the center having the flash tubes radiating therefrom toward the various burners. The spider constituted a separate unit and was arranged to rest on the burners by means of the flash tubes. This arrangement, however, was not very satisfactory because it is practically impossible to have the four cooking top burners supported in exactly the same plane, one or more are bound to be above or below the plane of the others, and in that way the flash tubes for certain burners are not properly positioned with respect thereto for quick lighting. It has also been common practice to have the lighter rigidly supported by itself and to have the cooking top burners resting on another support. That arrangement naturally meant too much chance for improper alignment of each burner with its flash tube and if anything was more objectionable than the other arrangement just described. It is, therefore, the principal object of my invention to provide for the rigid mounting of the lighter and the supporting of the burners directly on the ends of the flash tubes, whereby not only to eliminate certain parts that went with the old arrangement, and thus make for simplicity and economy, but, what is more important, also insure proper relationship of the burners with reference to the flash tubes for quick and positive lighting.

Another object is to provide quick detachability of the burners from this new form of support whereby to facilitate assembling and also make it easier to remove burners for inspection and cleaning.

Another object of the invention is to so construct the combination lighter and burner support that the same is interchangeable for use on stoves having right or left hand ovens. Furthermore, in the case of stoves which are not to be equipped with an automatic lighter, a support generally similar to the combination lighter and burner support can be provided by simply eliminating the lighter casing and merely providing an opening at that point for the projection therethrough of the ordinary flash type lighter; and providing solid arms in place of the hollow flash tubes for support of the burners.

The invention is illustrated in the accompanying drawings, in which—

Figure 1 is a plan view of the cooking top of a gas stove embodying my invention, the grates being removed to better disclose the invention; 5

Fig. 2 is a detail of the simmer burner support taken looking on the line 2—2 of Figure 1;

Fig. 3 is a cross-section taken on the line 3—3 of Figure 1, showing the combination lighter and burner support in side elevation; 10

Fig. 4 is an enlarged sectional detail taken on the line 4—4 of Figure 1, showing the quickly detachable connection between the burner and flash tube;

Fig. 5 is a similar section on the line 5—5 of 15 Figure 1, and

Fig. 6 is a section similar to Figs. 4 and 5 but showing a modified construction.

Similar reference numerals are applied to corresponding parts throughout the views. 20

Referring to Figure 1, the numeral 9 is applied to the frame of the cooking top alongside the oven section 10 which in this case is to the left of the cooking top but may, however, be to the right thereof, as is well known. The usual grates 25

provided for the cooking top and fitting in the recess 11 in the frame 9, have been removed better to disclose the cooking top burners 12—15 and the simmer burner 16, which have the usual mixers 17 where they make detachable connection with the cocks 18 on the manifold 19. The latter is shown as exposed but may, of course, be concealed. Heretofore, it was the practice to provide lugs on the burners 12—15 for supporting the same on a bracket or hanger reaching from one side of the cooking top to the other beneath the burners. An automatic lighter consisting of a pilot light casing at the center thereof with flash tubes radiating therefrom toward the various burners was then simply placed over the pilot light jet and allowed to rest by the ends of its flash tubes on the burners, one certain finger of each burner being provided with an end port for discharging into the flash tubes, and the automatic lighter being supported by its flash tubes on those particular fingers. Now, the fact that the burner support was so crude and there was no provision made to keep the burners from getting cocked out of position one way or another, and the burners were almost invariably never exactly in the same plane, naturally gave rise to the objection that the lighter would be in proper relation only to certain burners and not to others, and the automatic lighting of the cooking top burners would not be anywhere near uniform; 40

those having the proper relation to the lighter could be lit quickly, whereas the others would light very slowly, if at all. In the other arrangement above mentioned, where the lighter was rigidly supported by itself, entirely independently of 45

the burners, the lighter would be liable to fall off the burners if the burners were tilted, and the lighter would not be held in position by the burners; 50

and the burners would be liable to fall off the lighter if the lighter were tilted, and the burners would not be held in position by the lighter; 55

and the burners would be liable to fall off the lighter if the lighter were tilted, and the burners would not be held in position by the lighter; 60

the burners, the automatic lighting of the burners was even less likely to be uniform, for obvious reasons. The present invention avoids the objection noted by providing a novel construction 5 and arrangement of parts which will now be described.

The combination lighter and burner support is indicated generally by the reference numeral 20, and comprises a one-piece casting having the 10 hollow body or casing 21 of the pilot light not only cast integral with flash tubes 22—25, but also integral with supporting arms 26 and 27. The arms 26 and 27 constitute, in effect, a supporting bracket, the former having a cross portion 28 integral therewith fastened as by means of bolts 29 to a hanger 30 having lugs 31 and 32 for engagement above and below the supporting ledge 33 for rigid support at one end of the unitary casting, and the arm 27 having a lug 34 on the end 15 thereof arranged to rest on a ledge 35 to provide support at the other end. Obviously, the bolted connections 29 may be loosened to permit adjustment of the unit 20 relative to the hanger 30 if it does not come in the proper plane when assembled on the stove. The lugs 31—32 are spaced far enough to either side of the arm 26 to make the unit 20 quite rigid, and the three point support is, therefore, all that is necessary. It is also 20 obvious that the unit 20 can be quickly and easily 25 assembled into the stove and just as easily removed, by virtue of the construction described.

The flash tubes 22 and 25 extend in opposite directions from the casing 21 angularly with reference to the arm 27 for cooperation with the 30 front burners 12 and 15, respectively. The outer ends of these tubes are enlarged, as indicated at 36, for reception therein of the ends of the fingers of the burners in which the ports 37 for delivering gas through the flash tubes are provided, these ports being at a predetermined angle 35 to the plane of the tops of the burners, in accordance with the disclosure of the Methudy patent. The bottom walls of the flash tubes are cut away at the ends 36, as appears at 38, partly to admit secondary air for the jet at the end-most port 37 and partly also to facilitate making 40 detachable connection between the tubes and the fingers of the burners. A lug 39 is provided projecting from the end of each of the flash tubes 22 and 25 at one side of the enlarged portion 36 to 45 serve as supporting ledges for projections 40 provided on the same side of the fingers of the burners 12 and 15. Lugs 41, suitably cast integral with the fingers of the burners and projecting from the under side thereof, reach under the 50 ends of the flash tubes and engage under small transverse ribs 42 cast integral with the bottom wall of the tubes. From this description it should be evident that the front cooking top burners 12 and 15 are rigidly supported on the ends of the 55 flash tubes 22 and 25, respectively, with the end-most ports 37 on the fingers of the burners adapted to cooperate with the flash tubes disposed precisely in a predetermined desired relation to the ends of said tubes. There is, therefore, no 60 question as to the quick and positive lighting of these burners. The burners can be quickly and easily removed from connection with the flash tubes by tilting the same on the projections 40 as fulcrums and then shifting sidewise enough to bring the projections 40 clear of the lugs 39, whereupon the burners can be dropped down below the plane of the flash tubes and slipped off the cocks for removal from the stove. In the 65 installation of the burners it is only necessary

to be sure that the side of the finger bearing the projection 40 be brought into engagement with the lug 39 with the projection resting on top of the lug; that will bring the ports 37 in proper relation with the flash tube. 5

In the case of the rear cooking top burners 13 and 14, the connection between the burners and the flash tubes 23 and 24, respectively, is very much the same as that just described, excepting that the two lugs 39' are provided on the end of 10 the flash tubes at opposite sides of the fingers of the burners arranged to cooperate with the flash tubes, and projections 40' are provided on opposite sides of the fingers of the burners to rest on said lugs. Lugs 41' are provided extending 15 from the fingers for engagement under ribs 42' preferably made integral with the flash tubes. In this case, however, the ends of the lugs 41' are provided with shoulders 43 extending upwardly behind the ribs 42' whereby to hold the 20 burners against accidental displacement from connection with the flash tubes. Nothing of this sort is required in the case of the front cooking top burners, because in that case, as stated above, the side of the finger of the burner comes into 25 engagement with the side of the lug on the flash tube and movement of the burner away from the flash tube is prevented. In removing a burner it is only necessary to tilt it about the projections 40' as a fulcrum or trunnions so as to bring the 30 shoulder 43 clear of the rib 42', whereupon the burner can be withdrawn from connection with the flash tube by movement thereof sidewise away from the tube in a manner believed to be self-evident. In the installation of the burner, the 35 same is slightly tilted as the lug 41' is brought toward the end of the flash tube, and the projections 40' are brought over the tops of the lugs 39' and allowed to rest thereon. The burner is moved toward the flash tube until the projections 40' 40 come into engagement with the end of the tube, so as to insure the positioning of the shoulder 43 behind the rib 42'. In case the burner does not happen to be moved in far enough the shoulder 43 coming in contact with the inclined back face 45 of the rib 42' will cause the burner to be drawn toward the tube. It is obvious that each of the burners 13 and 14 is supported rigidly and with its end port 37 in proper relation to the flash tube for quick and positive lighting. It is perfectly clear that the relation of each burner to its flash tube is absolutely independent of the relation of said burner to the other burners. 50

As a modified or alternative construction, attention is called to Fig. 6 showing a bracket 45 formed 55 integral with the flash tube, indicated at 46, and providing support for the burner 47 adapted to rest on top thereof, as shown, in such a position that the end port 37 of the burner is properly related to the end of the flash tube for quick 60 and positive lighting. As a means of holding the burner in the position shown, pegs 48 may be provided on the bottom of the burner arranged to be received in sockets 49 provided in the bracket, or any other special formation may be provided 65 on the bracket for engagement by the burner with that object in view. It is believed that this construction might be preferred for the reason that it makes it easier to install the burners or remove the same, although it will be evident from the description of Figs. 4 and 5 that the interlocking connection has certain decided advantages. 70

The simmer burner 16 in the case of a stove having a left hand oven is placed to the right of the middle of the cooking top along with the so- 75

called giant burner 15, but in the case of a stove having a right hand oven, it is placed to the left of the middle of the cooking top, and the burners 15 and 12 are interchanged. The flash tubes 22 and 25 are made of the same length for cooperation with the burners 12 and 15 in either arrangement. The flash tubes 23 and 24 both have webs 50 cast integral therewith to serve as supporting ledges for cooperation therewith of a hook-shaped projection 51 formed integral with the end of the simmer burner 16. When the simmer burner is placed on either side of the unit 20 and supported by its projection 51 as just described, it is disposed immediately alongside a hollow neck 52 formed integral with the casing 21 of the lighter and, hence, is arranged to be lit practically the instant the gas is turned on. When the burner is disposed to the right of the unit 20, a tube 53 is extended from the neck 52 on the left hand side for the lighting of the oven burner, and vice versa.

In operation, assuming that a pilot burner is provided in connection with the casing 21, as indicated at 54 in Fig. 3, supplied with gas from the manifold 19 through a tube 55, when the gas for any one of the burners is turned on, a certain amount of gas is delivered through the flash tube cooperating with the burner from the endmost port of the burner and is ignited by the pilot light in the casing 21. A flash-back occurs through the flash tube and lights the burner. The definite location of each burner to its particular flash tube insures quick and positive lighting so that there is no odor of gas in the room.

In the case of stoves which are not to be equipped with an automatic lighter, a support may be provided for the burners generally similar to the support 20 but having simply an opening instead of the casing 21, for the projection therethrough of an ordinary flash type lighter, and provided with solid arms in place of the hollow flash tubes for support of the burners. In that way the burners are assured of proper relation to the lighter for quick and positive lighting.

It is believed that the foregoing description conveys a clear understanding of all of the objects and advantages of my invention. While reference has been made in the description to certain specific details of construction and arrangement, it should be understood that various changes may be made without departing from the spirit and scope of the invention. The appended claims have been drawn with a view to covering all legitimate modifications and adaptations.

I claim:

1. In a gas stove, the combination with the burners of the cooking top, of a lighter for said burners, means for supporting the lighter at a predetermined elevation with reference to the cooking top, and means for supporting each of the burners from the lighter and in operative relation thereto.

2. In a gas stove, the combination with the burners of the cooking top, of an automatic lighter comprising a pilot light casing having flash tubes extending therefrom toward the different burners, means for supporting the lighter at a predetermined elevation with reference to the cooking top, and means for supporting the burners on the ends of the flash tubes.

3. In a gas stove, the combination with the burners of the cooking top, of an automatic lighter comprising a pilot light casing having flash tubes extending therefrom toward the different burners, means for rigidly supporting the lighter at a pre-

determined elevation relative to the cooking top, and means for detachably connecting the burners with the outer ends of said flash tubes for support of the burners thereon in operative position with respect thereto.

4. In a gas stove, the combination of a plurality of burners for the cooking top, an automatic lighter comprising a pilot light casing having a plurality of flash tubes extending therefrom toward the different burners, one finger of each burner being provided with a port in the end thereof for the discharge of gas into the flash tube arranged to cooperate with the burner, means for supporting the casing independently of the burners and means whereby each burner is arranged to be individually supported and located by the flash tube associated therewith in operative position with respect to the flash tube.

5. In a gas stove, the combination of a plurality of burners for the cooking top, an automatic lighter comprising a pilot light casing having a plurality of flash tubes extending therefrom toward the different burners, one finger of each burner being provided with a port in the end thereof for the discharge of gas into the flash tube arranged to cooperate with the burner, means for rigidly supporting the lighter at a predetermined elevation with reference to the cooking top, and means on the flash tubes whereby each burner is arranged to be individually located in operative position with respect to its flash tube, the last mentioned means serving also to support each burner at a predetermined elevation with reference to the cooking top.

6. In a gas stove, the combination with the cooking top frame and the right and left hand burners of the cooking top, of a combination lighter and burner support comprising a casing disposed between the burners, flash tubes extending from the casing toward the different burners, the same having means on the ends thereof for individual support of the burners, and a supporting bracket extending in a fore and aft direction with reference to the frame between the right and left hand burners and serving to support the casing on the frame, said bracket having connection with the frame so as to prevent deflection of the casing and flash tubes out of a plane substantially parallel with the cooking top whereby to rigidly support the burners in a predetermined plane with reference to the cooking top.

7. A structure as set forth in claim 6 including a second bracket arranged to be made rigid with the frame for supporting the bracket thereon, and means providing a connection between the brackets whereby the first bracket is arranged to be adjusted with respect to the second bracket to position the lighter casing and flash tubes in a predetermined desired plane with reference to the cooking top.

8. In a gas stove, the combination of a plurality of cooking top burners, an automatic lighter for said burners comprising a pilot light casing having a plurality of flash tubes extending therefrom toward the different burners, means for supporting the casing independently of the burners and means on the lighter whereby each of the burners is individually supported permitting the setting of each burner independently of the others in operative relation to its flash tube.

9. In a gas stove, the combination with the burners of the cooking top, of a combination lighter and burner support comprising a casing

75

- having a plurality of flash tubes formed integral therewith and extending therefrom toward the different burners and also having supporting arms formed integral therewith for supporting the casing and flash tubes in a predetermined plane with reference to the cooking top, and means on said combination support whereby the burners are individually supported on the ends of the flash tubes.
10. In a gas stove, the combination with the burners of the cooking top, of a combination lighter and burner support comprising a casing having a plurality of flash tubes formed integral therewith and extending therefrom toward the different burners and also having supporting arms formed integral therewith for supporting the casing and flash tubes in a predetermined plane with reference to the cooking top, and means formed integral with the ends of the flash tubes for supporting the burners thereon.
11. In a gas stove, the combination with the burners of the cooking top, of a combination lighter and burner support comprising a casing having a plurality of flash tubes formed integral therewith and extending therefrom toward the different burners and also having supporting arms formed integral therewith for supporting the casing and flash tubes in a predetermined plane with reference to the cooking top, and means for individually supporting each burner on the end of the flash tube associated therewith, said means comprising a portion formed integral with the end of the flash tube, and a portion formed integral with the burner and arranged to engage the aforementioned portion to support the burner in operative relation to the end of the flash tube.
12. In a gas stove, the combination with the burners of the cooking top, of a combination lighter and burner support comprising a casing having a plurality of flash tubes formed integral therewith and extending therefrom toward the different burners and also having supporting arms formed integral therewith for supporting the casing and flash tubes in a predetermined plane with reference to the cooking top, and means for individually supporting each burner on the end of the flash tube associated therewith, said means comprising interlocking portions formed integral with the end of the flash tube and with the burner, said portions being constructed so as to support and lock the burner detachably in a predetermined operative relation to the end of the flash tube.
13. In a gas stove, the combination of a suitably supported lighter comprising a pilot light casing having a plurality of flash tubes extending therefrom in different directions for lighting different burners, a plurality of cooking top burners disposed adjacent and supported on the ends of the flash tubes, the pilot light casing being provided with laterally directed openings on opposite sides thereof, a simmer burner, means for supporting the simmer burner by either one of two of said tubes alongside said pilot light casing adjacent either of said openings, and a flash tube for lighting still another burner such as an oven burner arranged to communicate with the other opening.
14. In a gas stove, the combination of an automatic lighter comprising a pilot light casing having a plurality of flash tubes extending therefrom in different directions for lighting different burners, means for supporting the lighter at a predetermined elevation relative to the cooking top, a plurality of burners disposed adjacent the ends of the flash tubes and supported thereby in operative relation thereto, the pilot light casing being provided with laterally directed openings on opposite sides thereof, a simmer burner, means for supporting the simmer burner from the lighter on either side of the casing adjacent either of said openings, and a flash tube for lighting still another burner, such as an oven burner, arranged to communicate with the other opening.
15. In a gas stove, the combination of a pilot light casing, means for supporting the casing independently of a burner or burners adapted to cooperate therewith, a flash tube extending therefrom, a burner disposed adjacent the end of the flash tube and arranged to be ignited by flashback through the tube from the casing, the burner having an end port for discharging gas from the burner through the tube for ignition in the casing, and means for rigidly connecting the end of the flash tube and burner together in operative relation to one another to insure quick and positive lighting and so as to support the burner by means of the tube.
16. A structure as set forth in claim 15 wherein the last mentioned means comprises a lug projecting from the end of the flash tube, a projection on the burner arranged to rest on top of said lug, and a lug projecting from the burner and arranged to engage beneath the flash tube.
17. A structure as set forth in claim 15 wherein the last mentioned means comprises a pair of lugs projecting from the end of the flash tube at opposite sides thereof and adapted to receive a portion of the burner therebetween, projections on opposite sides of the latter arranged to rest on top of said lugs, and a lug on the burner extending underneath the flash tube and arranged for engagement therewith.
18. In a gas stove, the combination of a cooking top frame, a plurality of cooking top burners, and a combination lighter and burner support comprising a pilot light casing having a plurality of flash tubes extending laterally therefrom in different directions toward the different burners for lighting the same, and two arms reaching forwardly and rearwardly from the casing for support of the latter, the one arm having means laterally spaced with respect thereto to provide two points of support for the casing on the frame, and the other arm being arranged to rest on the frame at a third point, the three points of support determining the plane of the lighter with reference to the cooking top.
19. A structure as set forth in claim 18 including means for supporting the burners on the ends of the flash tubes, each in operative relation to its flash tube.
20. In a gas stove, the combination with the burners of the cooking top, of a unitary support therefor comprising a supporting bracket disposed at a predetermined elevation with reference to the cooking top, the same having a plurality of supporting arms projecting therefrom toward the different burners, each arm being arranged to support a burner thereon, and all of said arms being in a predetermined plane whereby to support the burners all in a predetermined plane, the said bracket having an opening provided therein at a predetermined position spaced with reference to said burners for reception of a pilot light for ignition of the burners.
21. In a gas stove, the combination with the burners of a cooking top, of a unitary support for said burners comprising a supporting bracket disposed at a predetermined elevation with ref-

erence to the cooking top, the same being provided with an opening at a central location with reference to said burners for reception of a pilot light for ignition of the burners, said bracket having arms radiating from said opening toward the different burners constructed to conduct flame from the pilot light to the burners for ignition thereof, and means on the arms for individually supporting the burners, all in a predetermined

5 plane with reference to the cooking top.

22. In a gas stove comprising a cooking top, burners therefor disposed in a suitable spaced relation to one another, and a lighter centrally located with respect to the burners to permit 10 lighting any of said burners with equal facility, means for supporting the lighter at a predetermined elevation with reference to the cooking top, and supports for the various burners radiating from the lighter to support the burners in 15 operative relation to the lighter and the cooking top.

23. An automatic lighter for gas stoves comprising a pilot light casing having flash tubes extending therefrom, means on the ends of the 20 flash tubes for supporting burners, and means extending from the pilot light casing for support of the lighter as a unit, together with the burners, at a predetermined elevation with respect to the cooking top of a gas stove.

24. In a gas stove comprising a cooking top, a plurality of burner devices therefor, a lighter having a plurality of lighting devices extending therefrom toward the burner devices, and a single means for supporting the lighting devices at 25 a predetermined elevation with respect to the cooking top, said lighting devices serving to support the other devices whereby to insure the correct operative relation between the burner devices and lighter devices.

25. In a gas stove, the combination with the 30 burners of the cooking top, of a bracket having burner supports extending therefrom to support the burners in a certain plane with respect to the cooking top, a pilot light housing on said bracket, and passages provided on the burner supports 35 for conducting gas from the burners to the pilot light housing for ignition, whereby to light the burners by flashback through said passages.

26. In a gas stove, the combination with the 40 burners of the cooking top, of a bracket having burner supports extending therefrom, a pilot light housing on said bracket from which the burner supports extend toward the different 45 burners, said burner supports having passages therein for conducting gas to the pilot light housing for ignition, whereby to cause flash-backs 50 through the passages to the burners for lighting purposes, each of said burners having top ports and each have a special end port from 55 which gas for lighting purposes is arranged to be discharged through the passage associated therewith, and means provided on the outer end of each of said supports for supporting the burners with the tops thereof in a certain plane with 60 reference to the outer ends of the passages and with the end ports in alignment and communication with said passages, the aforesaid bracket being disposed so as to support all of the burners 65 in a certain plane with reference to the cooking top.

27. In a gas stove, the combination with the 70 front and rear pairs of burners of the cooking top, of a supporting bracket extending in a fore and aft direction with reference to the cooking top between the right and left hand burners, a

lighter casing supported on the bracket centrally between the burners, burner supports on the bracket for locating the burners in operative positions with reference to the lighter casing and all in a certain plane with reference thereto, and means for supporting the bracket at its opposite ends so as to hold the set of burners along with the lighter casing in a certain plane with reference to the cooking top.

28. In a gas stove, the combination with the 10 burners of the cooking top, of a single support for all of said burners, a lighter casing carried on said support centrally with reference to the burners, said support having arms extending therefrom in different directions radiating from 15 the lighter casing, said arms having gas-conducting passages provided thereon communicating with the lighter casing, and means for individually supporting each burner on the end of the arm associated therewith, said means comprising a portion formed integral with the burner and a portion formed integral with the end of the arm and arranged to inter-engage with the aforementioned portion to support the burner in 20 operative relation to the end of the passage on 25 said arm.

29. In a gas stove, the combination of a suitably supported lighter comprising a pilot light casing having a plurality of gas conduits extending therefrom in different directions for lighting different cooking top burners, a plurality of burners disposed adjacent and supported upon the ends of the gas conduits, the pilot light casing being provided with a laterally directed opening independent of the conduits, and a sim- 30 mer burner supported by one of said conduits alongside the casing in direct flame propagating relation with the pilot light through said opening.

30. In a gas stove, the combination with the 35 cooking top burners, of a pilot light casing centrally disposed with reference to the burners and having gas conduits extending therefrom toward the different burners for lighting purposes, a bracket reaching fore and aft with respect to the cooking top between the left and right hand 40 burners and serving to support the pilot light casing, the one end of said bracket having means laterally spaced with respect thereto to provide two points of support for the casing with respect to the cooking top, and the other end of said 45 bracket having means providing a third point of support with respect to the cooking top, the three points of support determining the plane of the lighter with reference to the cooking top, and means for supporting the burners from the 50 bracket each in operative relation to one of the gas conduits.

31. In a gas stove comprising a cooking top and front and rear pairs of burners therefor, a 55 supporting bracket reaching fore and aft with reference to the cooking top between the right and left hand burners, means extending laterally from the bracket for supporting the right and left hand burners in a certain plane with 60 respect to the cooking top, said bracket having an opening provided therein centrally with respect to the burners, and a pilot light device in said opening.

32. In a gas stove, the combination with the 65 cooking top, of cooking top burners arranged to be supported in a certain horizontal plane with respect to the cooking top, lighting means for the burners comprising pilot light housing means and gas conducting means projecting laterally therefrom toward the burners for conducting gas 70

75 top between the right and left hand burners, a

from the burners for ignition by a pilot light in said housing means, means for supporting the lighting means independently of the burners in a predetermined plane with respect to the cooking top, and means for supporting the burners from the lighting means whereby to secure a desired operative relationship between the gas conducting means and the burners.

33. In a gas stove, the combination with the burners of the cooking top, of a suitably supported bracket structure including portions for supporting the burners at a predetermined plane relative to the cooking top, lighting means on said structure in operative relation to the burners, and gas conduits included in the burner supporting portions of said structure for flash-back lighting between the burners and lighting means.

34. In a gas stove, the combination with the burners of the cooking top, of a bracket suitably supported relative to the cooking top having a central opening for an igniter and supporting arms radiating from the opening to the burners for supporting the latter predetermined distances from the opening and at a predetermined elevation relative to the cooking top, and an igniter in said opening.

35. In a gas stove, the combination with the burners of the cooking top, of a bracket suitably supported relative to the cooking top having a central opening for an igniter and supporting arms radiating from the opening to the burners for supporting the latter predetermined distances from the opening and at a predetermined elevation relative to the cooking top, gas conduits for conducting gas from the burners along said arms to the opening for ignition by the igniter, and an igniter in said opening.

36. In a gas stove comprising a cooking top, burners in the four corners of the cooking top, a lighter frame extending in the middle of the cooking top between the two pairs of burners and rigidly supported relative to the cooking top independently of the burners, said lighter frame carrying pilot light housing means and gas conducting means, the latter projecting laterally from the housing means toward the various burners to cause flash-back ignition of the burners by conducting gas therefrom to the housing means, and means extending between the gas conducting means and the burners for supporting the burners in operative relation to the cooking top and the gas conducting means.

37. In a gas stove, the combination with the cooking top and the right and left hand burners of the cooking top, of a combination lighter and burner support comprising a casing disposed between the burners, flash tubes extending from the casing toward the different burners, the same having means on the ends thereof for individual support of the burners, and a support for the combination lighter and burner support extending from front to rear in the middle of the cooking top between the right and left hand burners, the combination lighter and burner support being supported thereby in a plane substantially parallel with the cooking top and at a certain elevation so as to support all of the burners in a certain plane with reference to the cooking top.

38. In a gas stove comprising a cooking top, a lighter for cooking top burners, means for supporting said lighter with reference to the cooking top, main and simmer burners for the cooking top, and means for supporting the main and sim-

mer burners from the lighter for lighting therefrom and in operative relation to the cooking top.

39. In a gas stove comprising a cooking top, an automatic lighter comprising a pilot light casing having flash tubes extending therefrom, means for supporting the lighter with reference to the cooking top, main and simmer burners for the cooking top, and means for supporting a main and simmer burner on the end of a flash tube in operative relation to the cooking top.

40. In a gas stove comprising a cooking top, burners in the four corners of the cooking top, a spider frame rigidly supported in a central position relative to the cooking top and providing arms extending therefrom toward the various burners, the outer ends of said arms being constructed to support the burners, whereby said frame constitutes a unitary burner support, and lighting means on said frame at the center thereof and substantially equi-distant from all of said burners.

41. In a gas stove comprising a cooking top, burners in the four corners of the cooking top, a spider frame rigidly supported in a central position relative to the cooking top and providing arms extending therefrom toward the various burners, the outer ends of said arms being constructed to support the burners, whereby said frame constitutes a unitary burner support, the arms being further constructed to provide gas conducting channels communicating at their outer ends with the burners, and a pilot light housing at the center of said frame substantially equi-distant from all of said burners and communicating with the inner ends of said channels.

42. In a gas stove comprising a cooking top, burners in the four corners of the cooking top, a spider frame rigidly supported in a central position relative to the cooking top and providing arms extending therefrom toward the various burners, the outer ends of said arms being constructed to support the burners, whereby said frame constitutes a unitary burner support.

43. In a gas stove, the combination with the cooking top, of a unitary lighter and burner assembly supported at a predetermined elevation relative to the cooking top and comprising a central lighter having a pilot light casing and flash tubes extending therefrom, and burners disposed in lighting relation to and rigid with the ends of said tubes, whereby all of said burners have the same lighting relation to the lighter and the same operative relation to the cooking top.

44. In a gas stove, the combination with the cooking top, of a lighter comprising a central pilot light casing and flash tubes rigid therewith and extending therefrom, cooking top burners at the outer ends of said tubes, and integral connections joining the burners to said tubes in operative relation thereto, whereby the lighter and burners form a unit arranged to be supported at a predetermined elevation relative to the cooking top with all of the burners having the same lighting relation to the lighter and the same operative relation to the cooking top.

45. In a gas stove, the combination with a cooking top, of a central lighter and burners surrounding the same and supported thereby so as to be all adapted to be lighted thereby in like manner.

STANLEY H. HOBSON.
